TYPE CLAMP

Charles J. Beck, Philadelphia, Pa.

Original application October 24, 1929, Serial No. 402,024. Divided and this application March 7, 1934, Serial No. 714,515

5 Claims. (Cl. 101—381)

The present application is a division of the applicant's application Serial No. 402,024, filed October 24, 1929, and relates to a particular means for clamping individual type slugs in a printing block which, while capable of general usage, is particularly adaptable for use in the machine forming the subject matter of the above noted parent application.

The construction and operation of the type clamp forming the subject matter of the present application will be fully disclosed hereinafter, reference being had to the accompanying drawing, of which:

Fig. 1 is a perspective view of a type block and slug clamp made in accordance with the principles of the invention; and

Fig. 2 is a sectional view taken on the line 2—2, Fig. 1.

As shown in the drawing, the type slugs 130 are of a T-type and are adapted to be clamped in printing position in a type block 131.

As shown in the drawing, the type block 131 in the present case is segmental in form. On the outer surface of the type block 131 are radially extending type-receiving grooves 135 into which are adapted to fit fins or lugs 136 which are formed integral with the cross or face plate 137 of the T-shaped type slugs 130.

The type-receiving grooves 135 are substantially equally spaced around the periphery 138 of the type block. Between each successive pair of grooves 135 is a radially extending groove 139 which provides a fin 140 adjacent one side of each of the type-receiving slots or grooves 135. At the opposite side of each of the type-receiving grooves 135 is formed a relatively heavy and rigid portion 141.

At spaced intervals along each of the grooves 139 the type block 131 is provided with tapered openings 142 which terminate in threaded openings 143 formed in the base or ungrooved inner portion 144 of the type block 131. The threaded openings 143 are adapted to receive correspondingly threaded screw members 145 which have frusto-conical heads 146 which are adapted to move axially into the tapered openings 142 when the screws 145 are tightened and thereby spread the relatively thin and more or less flexible portions 140 in opposite directions toward their adjacent type-receiving grooves 135, which reduces the width of the said type-receiving grooves and thereby clamps the fins 136 of the type slugs respectively within the said type-receiving grooves 135 with the face plate 137 of each slug

resting firmly on the outer face 138 of the block 131.

Obviously, the type block 131 may be flat instead of being curved in cross section for use in a flat bed machine instead of a curved bed or cylinder machine such as that disclosed in the above noted parent application without departing from the spirit of the invention.

I claim:

1. A type block having a type-receiving groove formed between a rigid wall and a relatively movable wall, a series of individual type slugs independently slidable to different positions in and along said groove, and means at predetermined relatively closely spaced points longitudinally of said groove for flexing the movable wall toward the rigid wall to clamp said type slugs therebetween.

2. A type block having a pair of substantially parallel type-receiving grooves, the outer walls of which are rigidly disposed in relation to each other and the inner walls of which are movable relative to said outer walls, a series of individual type slugs independently slidable to different positions respectively in at least one of said grooves, and means disposed intermediate said inner walls at predetermined relatively closely spaced points longitudinally of said grooves for spreading the same toward the said outer walls respectively to clamp said individual slugs in their adjusted positions respectively.

3. A type block having a pair of substantially parallel type-receiving grooves, the outer walls of which are rigidly disposed in relation to each other and the inner walls of which are movable relative to said outer walls, a series of individual type slugs independently slidable to different positions respectively in at least one of said grooves, said block having a third groove intermediate said type-receiving grooves, and a series of wedge elements adapted to said third groove at relatively closely spaced points along said third groove for spreading the said inner walls for the type-receiving grooves toward the said rigid walls thereof to clamp said individual slugs in their adjusted positions respectively.

4. A type block having a pair of substantially parallel type-receiving grooves, the outer walls of which are rigidly disposed in relation to each other and the inner walls of which are movable relative to said outer walls, said block having a third groove intermediate said type-receiving grooves, and a plurality of tapered openings spaced along and aligned with said third groove,

and tapered elements adapted to be forced into said tapered openings.

5. A type block having a pair of substantially parallel type-receiving grooves, the outer walls of which are rigidly disposed in relation to each other and the inner walls of which are movable relative to said outer walls, said block having a third groove intermediate said type-receiving grooves, and a plurality of circular tapered holes

spaced apart along and axially aligned with said third groove, said tapered holes having threaded extensions located in the block, and a plurality of screws adapted to said threaded extensions and having tapered heads adapted to said tapered holes for spreading the inner walls of the type grooves toward the said outer walls thereof respectively. 5

CHARLES J. BECK.
